APPARATUS FOR POLISHING SHEETS

Dwight D. Johnston, Versailles, Pa.

Application December 21, 1936, Serial No. 117,088

4 Claims. (Cl. 51—74)

This invention relates to an apparatus for polishing sheets, and particularly those sheets which are made of rather expensive metals, although not limited thereto.

5 In the past, considerable difficulty has been experienced in uniformly polishing the entire width of relatively thin sheets. It is among the objects of the present invention to overcome this difficulty.

10 Another object is to provide an inexpensive and efficient apparatus for uniformly polishing the entire width of sheets, regardless of variations in thickness.

The foregoing and other objects will be apparent after referring to the drawing, in which:

15 Figure 1 is an elevation, partly in section, of the device of the present invention.

Figure 2 is a sectional view on the line II—II of Figure 1.

20 Referring more particularly to the drawing, the numeral 12 designates a pair of opposed bearings in which there are mounted the opposite ends of a rotatable shaft 13 driven in any suitable manner (not shown). Mounted on the shaft 13 are a plurality of closely abutting assembled roll-sections 14, the peripheries of which are coated with a suitable abradant. These assembled roll-sections 14 constitute a polishing roll which is generally designated at A.

25 Immediately below and axially parallel the roll A is a cylindrical "billy" roll B having reduced end portions 16 which rotate in suitable bearings 17 and 17^a. The lowermost outer portions of the bearings 17 and 17^a are secured to individual vertical shafts 18 and 18^a, respectively. The lower ends of these shafts carry diaphragms 19 and 19^a, respectively. These diaphragms 19 and 19^a form part of a pair of conventional dash-pots, the latter being designated at 21 and 21^a, respectively.

30 The bearings 17 and 17^a are held against horizontal movement by side guides 22 which permit the roll B to be vertically reciprocated upon operation of the dash-pots 21 and 21^a.

In order to raise the "billy" roll B into contact with the polishing roll A, fluid under pressure is supplied to the dash-pots 21 and 21^a. This fluid pressure is obtained from a suitable source through a fluid line 25, which contains a constant pressure regulator 26. This regulator

35 supplies the fluid to a reserve tank 27 and thence to the dash-pots 21 and 21^a by lines 28, 29 and 30. According to the foregoing construction and arrangement of elements, the fluid pressure to the dash-pots 21 and 21^a will be equalized.

40 In operation, a thin sheet S to be polished is

laid on a carrier or waster sheet W and both are fed in any convenient manner between the rolls A and B, whereupon the upper side of the sheet S is polished by the polishing roll A. Both ends of the "billy" roll B are equally raised by the 5 diaphragms 19 and 19^a, thus raising it and the sheets W and S. In this manner the sheet S is made to firmly contact the polishing roll A under a constantly uniform pressure across the entire width thereof.

10 It frequently happens that the sheet S is of uneven thickness. For example, let it be assumed that the left-hand side of the sheet S of Figure 1 is considerably thicker than the right-hand side thereof. Under these circumstances 15 the "billy" rolls of the prior art yield downwardly at the point where the sheet is heaviest, but because of their construction and arrangement are also caused to move upwardly an equal amount at their opposite ends, thus badly "burning" the 20 sheet and possibly also warping it.

According to the teachings of the present invention, this condition is eliminated, as the "billy" roll B moves downwardly at the point where the excessive metal is present without any 25 other portion of the roll (such as the opposite end thereof) moving upwardly an equal amount. Thus, when the left-hand side of the "billy" roll B is downwardly displaced by the excess thickness of metal, it causes the bearing 17, shaft 18 30 and diaphragm 19 to also move downwardly a like amount, as indicated by the dotted lines in Figure 1. This action builds up abnormal fluid pressure in the lines 28 and 30, which is relieved by a bleeder 32 located in the reserve tank 27 when excess pressure is in either dash-pot. As soon as the excess metal has passed from between the rolls A and B, the pressure momentarily drops due to the loss of that volume of fluid which has been bled, but the constant pressure regulator 26 immediately opens and builds up once more the predetermined pressure, thus bringing both ends of the "billy" roll B to equal positions and pressure with relation to the abrading roll A.

It is obvious that should the heavy portion of the sheet S be present on the right-hand side of Figure 1, the bearing 17^a, shaft 18^a and diaphragm 19^a would move downwardly without effecting any substantial vertical movement of the left-hand side of the "billy" roll B. Should the heavy portion of the sheet S occur in the middle thereof, both ends of the "billy" roll B would move downwardly an equal amount, while heavy portions between the very center and one

edge of the sheet would divide the movement between the two floating ends in proportion.

While I have shown and described one specific embodiment of my invention, it will be understood that I do not wish to be limited exactly thereto, since various modifications may be made without departing from the scope of my invention, as defined by the following claims.

I claim:

- 10 1. Apparatus for polishing sheets and the like comprising, in combination, a power-driven rotatable polishing roll, an abrading medium carried by said polishing roll, an idle rotatable pressure roll disposed opposite and adjacent said polishing roll, separate fluid means for applying pressure to each of the ends of said pressure roll to influence the same towards said polishing roll, means for supplying fluid at constant pressure to each of said fluid means, and means for relieving excess fluid pressure in either of said fluid means without substantially varying the fluid pressure in the other of said fluid means.
- 15 2. Apparatus for polishing sheets and the like comprising, in combination, a power-driven rotatable polishing roll, an abrading medium carried by said polishing roll, an idle rotatable pressure roll disposed opposite and adjacent said polishing roll, separate fluid means for applying pressure to each of the ends of said pressure roll to influence the same towards said polishing roll, common means for supplying fluid at constant pressure to each of said fluid means, and means for relieving excess fluid pressure in either
- 20
- 25
- 30

of said fluid means without substantially varying the fluid pressure in the other of said fluid means.

3. Apparatus for polishing sheets and the like comprising, in combination, a power-driven rotatable polishing roll, an abrading medium carried by said polishing roll, an idle rotatable pressure roll disposed opposite and adjacent said polishing roll, separate fluid means for applying pressure to each of the ends of said pressure roll to influence the same towards said polishing roll, means for supplying fluid at constant pressure to each of said fluid means, and common means for relieving excess fluid pressure in either of said fluid means without substantially varying the fluid pressure in the other of said fluid means.

4. Apparatus for polishing sheets and the like comprising, in combination, a power-driven rotatable polishing roll, an abrading medium carried by said polishing roll, an idle rotatable pressure roll disposed opposite and adjacent said polishing roll, separate fluid means for applying pressure to each of the ends of said pressure roll to influence the same towards said polishing roll, common means for supplying fluid at constant pressure to each of said fluid means, and common means for relieving excess fluid pressure in either of said fluid means without substantially varying the fluid pressure in the other of said fluid means.

DWIGHT D. JOHNSTON.
